UNITED STATES PATENT OFFICE.

JOSEPH E. GAGNON, OF PHILADELPHIA, AND OSCAR B. ANDERSON, OF CHESTER, PENNSYLVANIA, ASSIGNORS TO KEYSTONE TYPE FOUNDRY, OF PHILADELPHIA, PENNSYLVANIA, A CORPORATION OF PENNSYLVANIA.

DESIGN FOR A PRINTER'S-CASE STAND.

52,095.

Specification for Design.

Patented June 11, 1918.

Application filed February 1, 1915. Serial No. 5,577. Term of patent 14 years.

To all whom it may concern:

Be it known that we, JOSEPH E. GAGNON, a citizen of the United States, residing at Philadelphia, Philadelphia county, and State of Pennsylvania, and OSCAR B. ANDERSON, a citizen of the United States, residing at Chester, Delaware county, and State of Pennsylvania, have invented a certain new, original, and ornamental Design for a Printer's-Case Stand, of which the following is a specification.

The design consists of the attractive form and arrangement of parts, as well as the attractive appearance of the cabinet as a whole in assembled form, as shown in the accompanying drawing, which is a perspective view of a printer's case stand, showing our new design.

What we claim is:

The ornamental design for a printer's case stand, as shown in the accompanying drawing.

In witness whereof we have hereunto set out hands and seals at Chester, Pennsylvania, this 30th day of December, A. D. nineteen hundred and fourteen.
